FIG. 7 is a rear view thereof;
FIG. 8 is a left side view thereof;
FIG. 9 is a right side view thereof;
FIG. 10 is a top view thereof;
FIG. 11 is a bottom view thereof;
FIG. 12 is a front perspective view thereof of its component 2;
FIG. 13 is a front view thereof;
FIG. 14 is a rear view thereof;
FIG. 15 is a left side view thereof;
FIG. 16 is a right side view thereof;
FIG. 17 is a top view thereof;
FIG. 18 is a bottom view thereof;
FIG. 19 is a front perspective view thereof of its component 3;
FIG. 20 is a front view thereof;
FIG. 21 is a rear view thereof;
FIG. 22 is a left side view thereof;
FIG. 23 is a right side view thereof;
FIG. 24 is a top view thereof;
FIG. 25 is a bottom view thereof;
FIG. 26 is a front perspective view thereof of its component 4;
FIG. 27 is a front view thereof;
FIG. 28 is a rear view thereof;
FIG. 29 is a left side view thereof;
FIG. 30 is a right side view thereof;
FIG. 31 is a top view thereof;
FIG. 32 is a bottom view thereof;
FIG. 33 is a front perspective view thereof of its component 5;
FIG. 34 is a front view thereof;
FIG. 35 is a rear view thereof;
FIG. 36 is a left side view thereof;
(Continued)

FIG. 37 is a right side view thereof;
FIG. 38 is a top view thereof; and,
FIG. 39 is a bottom view thereof.

1 Claim, 9 Drawing Sheets
